VISCOSITY REGULATOR

Harry T. Booth, Freeport, N. Y., assignor, by
mesne assignments, to Lubrication Control
Corporation, Chicago, Ill., a corporation of
Delaware

Application March 26, 1932, Serial No. 601,409

17 Claims. (Cl. 123—196)

This invention relates to viscosity regulators and has for an object a simple, efficient, inexpensive and durable apparatus for use in connection with the lubricating system of an internal combustion engine for regulating the viscosity of the lubricant supplied to the bearings.

In an apparatus embodying the invention, the lubricating oil of an internal combustion engine is delivered from the pump to a valve box having two outlets, each being connected with a pipe coil, one of the pipe coils being arranged within a chamber included in the cooling system between the engine jacket and the radiator and the other coil being arranged around said chamber. The two coils discharge into a conduit leading to the bearings. In the valve box there is provided a valve adapted to close either of the outlet ports, this valve being operated by pressure developed in a viscosity responsive device connected to the discharge conduit.

The oil flows solely through the inner coil except when its viscosity tends to decrease below a predetermined value, whereupon oil is diverted through the outer coil in sufficient quantity to supply oil of desired viscosity to the bearings. During the initial period of operation of the engine, the viscosity of the oil is high and the oil is directed through the inner coil and also during the same period, the temperature of the water delivered from the engine jacket to the chamber is higher than that of the oil passing through the inner coil and the oil is heated by the water, thereby decreasing the viscosity of the oil. After a period of operation, the temperature of the oil exceeds that of the water and then the water tends to cool the oil to prevent undue decrease of its viscosity. Should the viscosity of the oil tend to decrease below a predetermined value, a portion of the oil is diverted through the exterior coil in which it is air cooled to increase its viscosity. When the viscosity of the oil delivered to the bearings tends to increase above the predetermined value, the amount of oil diverted through the exterior coil is decreased and the amount of oil flowing through the inner coil is correspondingly increased.

Other objects, novel features and advantages of this invention will be apparent from the following specification and accompanying drawing, 50 wherein:

Fig. 1 is a side elevation of an automobile engine equipped with a viscosity regulator embodying the invention;

Fig. 2 is an enlarged vertical sectional view of 55 the regulator;

Fig. 3 is a section on the line 3—3 of Fig. 2; and Fig. 4 is a section through a viscosity responsive device.

The engine 10 is provided with a water outlet from its jacket to which is connected a pipe 11 leading into one end of a chamber 12 supported at the side of the engine. A conduit 13 leads from the other end of the chamber 12 to the radiator 14. A coil 15 is arranged within the chamber 12 and a coil 16 is arranged around the chamber 12. A valve box 17 is mounted on one end of the chamber and has outlets communicating with the coils 15 and 16. A pipe 18 leads from the lubricant pump (not shown) into the valve box 17. A valve 19, in the form of a piston, is slidably mounted in the valve box or casing 17 and in one position closes one outlet with the other open and in another position it closes the second outlet with the first outlet open, thus establishing connection between the pipe 18 and the two coils 15 and 16. The coils 15 and 16 discharge into a conduit 20 leading to the bearings of the engine.

A viscosity meter consisting of a viscosity responsive device 21 and a pressure gauge 23 is connected to the pipe 20 and has an outlet pipe 22 discharging into the sump of the engine 10. The pressure developed in the viscosity responsive device during its operation is applied to the gauge 23 through the medium of a pipe 24 leading from the meter to the gauge. A pipe 25 leads from the pipe 24 to the valve box 17 to which it is connected in such manner that the pressure developed in the viscosity responsive device 21 is applied to one end of the valve 19. A spring 26 bears against the other end of the valve 19 and tends to oppose movement of the piston under the influence of the pressure developed in the viscosity responsive device as well as to restore the piston to original position after having been moved by the pressure. An adjusting screw 27 is provided for regulating the pressure exerted by the spring 26.

When the engine is at rest there is no pressure developed in the viscosity responsive device and the valve 19 is maintained by the spring 26 in such position that the port leading to the coil 16 is opened and the port leading to the coil 15 is closed. When the engine is started, the viscosity of the oil is high and a high degree of pressure is immediately developed in the viscosity responsive device 21, which pressure being applied to the valve 19 moves the same against the action of the spring 26 into the position shown in Fig. 3 with the port leading to the coil 16 closed and

the port leading to the coil 15 opened, thereby directing the oil through the coil 15. During the initial period of operation of the engine, the water delivered from the engine jacket to the 5 chamber is of higher temperature than the oil and therefore heats the oil, tending to reduce its viscosity. The pressure developed by the viscosity responsive device thereupon diminishes but remains sufficient to maintain the valve 19 10 in the position shown in Fig. 3. Continued operation of the engine results in an increase in temperature of the oil above that of the water so that the water then tends to cool the oil to prevent undue decrease of viscosity. Should the 15 oil viscosity continue to decrease the pressure developed in the viscosity responsive device will further diminish until it permits the spring 26 to actuate the valve 19 to tend to open the port leading to the coil 16 and to tend to close the port 20 leading to the coil 15. A portion of the oil is then diverted through the coil 16 in which it is air cooled, thereby tending to cause increase in its viscosity. As the viscosity of the oil in the 25 conduit 20 increases, the pressure developed by the viscosity responsive device increases thereby tending to return the valve 19 to the position shown in Fig. 3 to reduce the flow through the coil 16 and increase the flow of the oil through the coil 15. A repetition of the cycle above outlined 30 maintains the viscosity of the lubricant approximately at a predetermined value, the value being dependent upon the pressure developed by the spring 26, which pressure can be regulated to meet different conditions. When 35 the engine is stopped the viscosity meter ceases to develop pressure and the valve 19 is again moved to the left under the influence of the spring 26 to its original position.

The above described apparatus maintains the 40 lubricating oil of an internal combustion engine approximately at a predetermined viscosity value irrespective of the initial viscosity rating of the oil and irrespective of dilution. The water of the circulating system tends to maintain the 45 oil at such temperature that its viscosity is maintained approximately at a predetermined value and the air cooled coil provides supplemental means for maintaining the oil at approximately the desired viscosity value in the event that the 50 viscosity of the oil tends to decrease below the predetermined value. Drainage ports 28 are provided in the valve box 17 and discharge either into the atmosphere or into a receptacle such as the oil reservoir. These drainage ports permit 55 the escape of any oil which may work past the piston 19 and thus prevent the development of any back pressure which might interfere with the proper operation of the valve.

The viscosity responsive device 21 consists of 60 a housing divided into three chambers by partitions 29 and 30. A pipe 31 leads from the pipe 20 to the middle chamber and the pipe 24 leads from the left hand chamber to the pressure gauge 23, the pipe 22 leading from the right 65 hand chamber. The partition 29 is provided with an orifice 29a, the resistance of which to liquid flow is substantially independent of the viscosity of the liquid and a friction tube 33 leads from the left hand chamber to the right 70 hand chamber, the resistance of the friction tube to liquid flow being dependent upon the viscosity of the liquid. The partition 30 is provided with a port which is adapted to be closed by a spring 75 actuated valve 34, this valve serving to maintain constant pressure in the middle chamber. Oil is

supplied to the middle chamber through the pipe 31 and flows through the orifice and friction tube at the same rate and is then discharged into the right hand chamber from which it is discharged through the pipe 22 into the sump and constant 5 pressure is maintained within the middle chamber by means of the relief valve 34, the pressure of oil in the pipe 31 being at all times greater than the pressure required to actuate the valve 34. As constant pressure is maintained in the 10 middle chamber, oil is supplied to the orifice at constant pressure and as its resistance to flow is independent of viscosity and the rate of flow through the orifice and the friction tube is the same, the pressure of the oil in the left hand 15 chamber is a measure of the rate of flow through the friction tube and is a function of the oil viscosity. Change in the oil viscosity results in change of pressure applied to the gauge 23 and to the piston 19 to control flow through the coils 20 as above explained.

Although the invention has been specifically disclosed as applied to the lubricating system of an internal combustion engine, it is to be understood that the invention is applicable to any 25 liquid system in which accurate viscosity regulation is desired. It is, of course, further understood that various modifications may be made in the structure of the system without in any way departing from the spirit of the invention as defined in the appended claims.

I claim:

1. In combination with the lubricating system of an internal combustion engine, a plurality of means for attemperating the oil in the system and discharging into a common conduit, means for flowing oil through said conduit under pressure, a viscosity responsive device including a chamber wherein the pressure of oil flowing therethrough is a function of its viscosity, a 40 branch pipe leading to said chamber from said conduit, valve means for controlling flow of oil through said attemperating means, and means for applying pressure developed in the chamber directly to said valve means to actuate the same. 45

2. In combination with the lubricating system of an internal combustion engine, a plurality of means for attemperating the oil in the system and discharging into a common conduit, means for flowing oil through said conduit under pressure, a viscosity responsive device including a chamber wherein the pressure of oil flowing therethrough is a function of its viscosity, a branch pipe leading to said chamber from said conduit, a reciprocating valve for controlling flow through said attemperating means, means for applying pressure developed in the chamber directly to one end of said valve, and means for applying pressure to the opposite end of said valve. 55

3. In combination with the lubricating system of an internal combustion engine, a plurality of means for attemperating the oil in the system and discharging into a common conduit, means for flowing oil through said conduit under pressure, a viscosity responsive device including a 60 chamber wherein the pressure of oil flowing therethrough is a function of its viscosity, a branch pipe leading to said chamber from said conduit, a reciprocating valve for controlling flow through said attemperating means, means for applying pressure developed in the chamber directly to one end of said valve, and resilient means bearing against the opposite end of said valve. 65

4. In combination with an internal combustion engine having a cooling system, a chamber 70

75

5 forming part of said cooling system, a coil of pipe in said chamber, a coil of pipe exterior of said chamber, a conduit into which both of said coils discharge, an oil supply pipe, a valve box having ports communicating with said coils and with said pipe, a valve mounted in said valve box, means for flowing oil through said conduit under pressure, a viscosity responsive device including a chamber wherein the pressure of oil flowing therethrough is a function of its viscosity, a branch pipe leading to said chamber from said conduit, and means for applying pressure developed in the chamber directly to said valve to actuate the same.

10 5. In combination with an internal combustion engine having a cooling system, a chamber forming part of said cooling system, a coil of pipe in said chamber, a coil of pipe exterior of said chamber, a conduit into which both of said coils discharge, an oil supply pipe, a valve box having ports communicating with said coils and with said pipe, a reciprocating valve mounted in said valve box, means for flowing oil through said conduit under pressure, a viscosity responsive device including a chamber wherein the pressure of the oil flowing therethrough is a function of its viscosity, a branch pipe leading from said conduit to said chamber, means for applying pressure developed in the chamber directly to one end of said valve, and means for applying pressure to the opposite end of said valve.

15 6. In combination with an internal combustion engine having a cooling system, a chamber forming part of said cooling system, a coil of pipe in said chamber, a coil of pipe exterior of said chamber, a conduit into which both of said coils discharge, an oil supply pipe, a valve box having ports communicating with said coils and with said pipe, a reciprocating valve mounted in said valve box, means for flowing oil through said conduit under pressure, a viscosity responsive device including a chamber wherein the pressure of the oil flowing therethrough is a function of its viscosity, a branch pipe leading from said conduit to said chamber, means for applying pressure developed in the chamber directly to one end of said valve, and resilient means bearing against the opposite end of said valve.

20 7. In combination with an internal combustion engine having a cooling system, a chamber forming part of said cooling system, a coil of pipe in said chamber, a coil of pipe exterior of said chamber, a conduit into which both of said coils discharge, an oil supply pipe, a valve box having ports communicating with said coils and with said pipe, a valve piston arranged in a cylinder provided in the valve box, means for flowing oil through said conduit under pressure, a viscosity responsive device including a chamber wherein the pressure of the oil flowing therethrough is a function of its viscosity, a branch pipe leading from said conduit to said chamber, a pressure carrying pipe leading from said chamber to one end of said cylinder and a resilient member exerting pressure on said piston tending to move the same in one direction.

25 8. A fluid system comprising two fluid paths, a conduit into which said paths discharge, means for flowing fluid through said conduit under pressure, attemperating means in one path, valve means movable back and forth for controlling flow through said paths, viscosity responsive means including a chamber wherein the pressure of the fluid flowing therethrough is a function of its viscosity, a branch pipe leading from said

30 conduit to said chamber, means for applying the pressure in said chamber to said valve means to actuate the same in one direction, and resilient means opposing such movement of said valve means.

35 9. In a fluid system, a valve casing, two passageways communicating with said valve casing, a conduit into which fluid flowing through both passageways discharges, a valve member in said casing movable back and forth to control flow through said passageways, a heat exchange device in one of said passageways, a viscosity responsive device including a chamber wherein the pressure of the fluid flowing therethrough varies with its viscosity, means to flow fluid from said system through said viscosity responsive device, a third passageway connecting said chamber and said casing for applying pressure developed in said chamber to said valve member to move it in one direction, and yielding means opposing such movement of said valve member.

40 10. In a fluid system, two passageways, a valve casing having ports communicating with said passageways, a heat exchange device in one of said passageways, means for flowing oil through said passages under pressure, a valve member movable back and forth in said casing to control flow through said ports, a conduit into which said passageways discharge, means for flowing fluid through said conduit under pressure, a viscosity responsive device including a chamber wherein the pressure of fluid flowing therethrough is a function of its viscosity, a branch pipe leading from said conduit to said chamber, and a pipe leading from said chamber to said casing for applying to said valve member the pressure developed in said chamber.

45 11. In a lubricating system for internal combustion engines, a heat exchange unit, a conduit leading to and away from said unit, means for flowing oil through said conduit under pressure, a bypass around said unit, viscosity responsive means including a chamber wherein the pressure of oil flowing therethrough is a function of its viscosity, a pipe leading from said conduit to said chamber, the junction of said bypass and conduit lying between said heat exchange unit and the junction of said pipe with said conduit, a valve for controlling flow through said heat exchange unit and bypass, and means for applying the pressure in said chamber to said valve to effect movement thereof.

50 12. In a lubricating system for internal combustion engines, a heat exchange unit, a conduit leading to and away from said unit, means for flowing oil through said conduit under pressure, a bypass around said unit, valve means for controlling flow through said unit and said bypass and comprising a casing having inlet and outlet ports, a valve piston movable in said casing, viscosity responsive means including a chamber wherein the pressure of oil flowing therethrough is a function of its viscosity, a pipe leading from said conduit to said chamber, the junction of said bypass and said conduit lying between said heat exchange unit and the junction of said pipe with said conduit, and connections between said chamber and said casing for applying to said valve piston the pressure developed in said chamber.

55 13. In a fluid system, two fluid paths discharging into a conduit, a heat exchange device in one path, means for flowing fluid through said conduit under pressure, a casing communicating with said fluid paths, a piston in said casing for

- controlling flow through said paths, a viscosity responsive device including a chamber wherein the pressure of fluid flowing therethrough is a function of its viscosity, a branch pipe leading from said conduit to said chamber, a pressure-carrying pipe leading from said chamber to one end of said casing, and a resilient member tending to oppose movement of said piston in one direction.
- 10 14. In a fluid system, two fluid paths, a heat exchange device in one path, a conduit into which said paths discharge, valve means for controlling flow through said paths, a chamber having a port comprising a friction tube and another port comprising an orifice, means for flowing fluid through said conduit to one of said ports at constant pressure, and means for applying to said valve means the fluid pressure in said chamber.
- 15 15. In an oil circulating system, an oil path, a heat exchanger in said path, a by-pass around said heat exchanger, viscosity responsive means exterior of said path and communicating therewith exterior of the ends of said by-pass and including a chamber wherein the pressure of the oil flowing therethrough is a function of its viscosity, and a valve movable to and fro to control flow through said heat exchanger and having
- applied thereto in one direction the pressure developed in said chamber.
16. In an oil circulating system, two paths, a conduit communicating with said paths, a heat exchange device in one of said paths, viscosity responsive means exterior of said conduit and connected thereto for operation upon by a portion of the oil flowing through the conduit and including a chamber wherein the pressure of the oil flowing therethrough is a function of its viscosity, and a valve movable to and fro to control flow through said heat exchanger and having applied thereto in one direction the pressure developed in said chamber. 5
17. In combination, a circulatory oil path divided over a portion of its length into two channels, means for circulating oil through said path, a cooler in one channel, a viscosity responsive device including a chamber wherein the pressure of oil flowing therethrough is a function of its viscosity, a branch path for flowing oil from said first path through said viscosity responsive device, and a valve movable to and fro to control flow through said cooler and having applied thereto in one direction the pressure developed in said chamber. 10 20 25
